BED

Ralph B. Hosner, San Francisco, Calif.

Application November 21, 1932, Serial No. 643,669

6 Claims. (Cl. 5—21)

My invention relates to a bed, and more particularly to a couch type of bed which may be extended to increase its sleeping capacity, such as a studio couch.

5 It is among the objects of my invention to provide a bed of the character described in which a foldable section is supported independently of the body section.

Another object of my invention includes the 10 provision of semi-automatic means for effecting the opening of the bed.

Still another object of my invention is to provide improved means for connecting the bed sections together.

15 A further object of my invention is to provide improved mechanism for elevating and collapsing the movable frame of the foldable bed section.

The invention possesses other objects and features of advantage, some of which, with the foregoing, will be set forth in the following description of my invention. It is to be understood that I do not limit myself to this disclosure of species of my invention, as I may adopt variant 20 embodiments thereof within the scope of the claims.

25 Referring to the drawings:

Figure 1 is an end view of the bed embodying my invention, and shows the same in closed position.

30 Figure 2 is a side view of the bed showing the foldable section extended and its movable frame ready to be elevated; and

Figure 3 is a similar view showing the movable frame in the process of being elevated; and

35 Figure 4 shows the bed completely opened.

Figure 5 is a detail view taken in the direction of the arrow 5 in Figure 4, and shows the hinge connection between the movable frame and base of the foldable bed section.

40 Figure 6 is a plan view showing the bed in its opened position.

Figure 7 is a vertical sectional view taken in the plane indicated by the line 7—7 of Figure 6, and shows the details of the latch construction.

45 Figure 8 is a side elevational view showing a modified form of the foldable bed section construction.

Figure 9 is a fragmentary plan view taken in the direction indicated by the arrow 9 of Figure 8, 50 and illustrates the means for locking the spacing bars.

Figure 10 is a detail elevational view taken in the direction indicated by the arrow 10 of Figure 9, and shows the lever control for the lock.

55 In terms of broad inclusion, the bed embody-

ing my invention comprises a fixed frame and a frame supported independently of the fixed frame and movable from a retracted position under the fixed frame to an extended position alongside and at an elevation common with the fixed frame. 60 Means are provided connecting the frames together for guiding the movable frame in its extending and retracting movements. Means are also preferably provided for urging the movable frame toward its extended position, and a latch 65 is preferably provided for holding the movable frame in its retracted position. A base is provided for supporting the movable frame, and the latter is mounted on the base so that it is movable from a collapsed position on the base to an 70 elevated position above the base; the collapsible feature of the movable frame on its base being provided so that the movable frame may clear the fixed frame when in its retracted position under the latter. Means are also provided on the base, 75 operable upon movement of the frame to its elevated position, for holding the same in said elevated position.

In greater detail, and referring particularly to Figures 1 to 7, the preferred form of bed embodying my invention comprises a body section 2 and an independently supported foldable section 3. The body section 2 comprises a fixed spring frame 4 held by a suitable supporting structure including 85

floor engaging legs 6. The foldable section 3 of the bed comprises a spring frame 7 which is movable from a folded or retracted position under the fixed frame, as shown in Figure 1, to an open or extended position alongside and at an elevation common with 90 the fixed frame, as shown in Figure 4. The foldable bed section 3 also includes a base 8 for supporting the movable frame 7. The base 8 is preferably in the nature of a box in which bed clothing may be stored. To afford mobility and to 95 provide independent support for the frame 7, the base 8 is mounted on suitable floor engaging rollers 9.

Means are provided for guiding the foldable section 3 in its extending and retracting movements. For this purpose a linkage is provided, preferably comprising a pair of crossed equalizing arms 11. These arms are pivoted together adjacent their center, and each is pivoted at one end to the supporting structure of the body 105 section 2 and at the other end to the base 8 of the foldable section 3. One of the pivots at the end of each of the arms is allowed to work in a suitable slot, as is common practice with an equalizing linkage of this type. The pivots at 110

the junction of the arms 11 and the body section 2 are preferably of a permanent nature, while the pivots at the junctions of the arms and the folding section 3 are preferably such that they 5 may be readily released to disconnect the bed sections.

As best shown in Figure 2, the junction between the arms 11 and the section 3 is preferably effected by providing a socket 12 on the base 8 into 10 which a pivot pin 13 on an arm 11 may project. To free the arm it is only necessary to lift the pin 13 from its socket. By this construction the two sections of the bed may be readily connected and disconnected, which is an important feature 15 in connection with the transportation of the bed.

Still referring to Figure 2, the equalizing arms 11 are preferably supported at their intersection by a leg 14 provided with a floor engaging roller or caster 16. This supporting leg stabilizes the 20 equalizing arms and materially improves the practical operation of the bed. A spring 17 is provided and is operatively connected between the two sections of the bed for the purpose of urging the foldable section 3 toward its extended 25 position. The spring is preferably interposed between the equalizing arms 11, as best shown in Figure 6.

Means are also provided for latching the foldable section 3 in its retracted position, as shown 30 in Figure 1. As best shown in Figures 6 and 7, this latch preferably comprises a hook 18 pivoted on the base 8 and engageable with a complementary hook 19 on the body section 2. The hook 18 is released by a push button 21 positioned 35 on the front end of the base 8. As shown in Figure 7, the button is mounted on the end of a lever 22 connected to the hook 18 by a suitable rod 23. A spring 24 is provided for holding the latch engagement. In order to extend the foldable section of the bed it is merely necessary to press the 40 button 21.

As best shown in Figures 1 to 4, the movable spring frame 2 of the foldable bed section 3 is mounted on its supporting base 8 so that it may 45 be moved from a collapsed position on the base to an elevated position where it lies in the plane defined by the fixed spring frame 4 of the body section 2. Preferably the movable frame 7 is pivotally and slidably mounted on the base 8. 50 This is effected by suitable hinges 26 which are fixed to the frame 7 and slidably connected to the base 8. As shown in detail in Figure 5, the upper wing of a hinge 26 is securely fastened to the frame 7, while the lower wing of the hinge 55 is provided with a slot 27 engaged by the studs 28 mounted on a plate 29 which is fastened to the base 8.

Spacing means are provided for holding the frame 7 in its elevated position. To this end a bar 31 is provided at each end of the base 8 and is pivotally connected to a fixed element 32 secured to the base by means of a pair of parallel arms 33. A spring 34 connected between one of the arms 33 and the fixed element 32 is arranged 65 to urge the spacing bar 31 toward its raised position, and a stop pin 36 is provided for holding the bar in this position. The spring 34 is sufficiently heavy to raise the bar 31 and to hold the same against the forward thrust of the frame 7 in the final act of elevating the frame, as will be 70 understood from the following.

Considering the mechanism thus far described, the actions involved in elevating the movable frame 7 are as follows: An operator grasps the 75 forward edge of the frame 7 and swings the same

up to a position as shown in Figure 3. As the frame swings out it is followed up by the spacing bar 31 due to the action of the spring 34. The operator then allows the frame 7 to swing down again. During this downward swing the frame moves into engagement with the spacing bars 31, and subsequent movement is a hinging of the frame about the rear ends of the bars. This latter movement is permitted by an upward sliding of the hinges 26.

When the frame finally comes to rest it is supported by the spacing bars 31, as shown in Figure 4. Of course the links 33 of the spacing bars are of such length that the frame 7 is at the same elevation as the fixed frame 4 of the body section 2. It will be seen that the elevating of the frame 7 is accomplished by two simple motions imparted by an operator, namely, swinging the frame 7 up and then letting it down again.

Means are provided for effecting a collapsing of the frame 7 to its position as shown in Figure 2, so that the folding section 3 may be retracted into the body section 2. For this purpose a link 38 is provided at each end of the frame 7 pivotally connected at one end to the frame and slidably pivoted at the other end to the spacing bar 31 in a suitable slot 39. The lower edge of the slot 39 is provided with a recess 41 into which the pivot pin 42 on the end of the arm 38 may drop.

The actions in collapsing the frame 7 from its elevated position are as follows: The outer edge of the frame is grasped by the operator and is again swung up to the position shown in Figure 3. This time the operator allows the frame 7 to swing back very slowly, so that the arm pin 42 will drop into the recess 41. Having the pin engaged in the recess, further lowering of the frame 7 causes the spacing bar 31 to swing down into its folded position. Of course the presence of the pin 42 in the recess 41 is only necessary in 115 overcoming the inertia of the spring 34 and starting the spacing bar 31 down, the final collapsing of the spacing bar being effected by the frame 7 bearing down on the bar.

In order to prevent the pin 42 from engaging 120 the recess 41 when the frame 7 is being raised to its elevated position, a hump 43 is provided adjacent the recess, as shown in Figure 3. When the frame is let down quite rapidly the presence of the hump 43 will cause the pin 42 to jump over the 125 recess 41. From the above it will be seen that the collapsing of the frame 7 also requires but two simple motions imparted by an operator, namely, an up and down swinging movement of the frame.

A modified form of the invention is shown in Figures 8, 9 and 10. Here it will be observed that a link 44 pivoted to the frame 7 is slidably pivoted to the base 8 by means of a pin 46 working in a guide groove 47. A notch 48 provided in the guide 135 is arranged to receive the pin 46 for holding the frame 7 in its upwardly tilted position.

In the present form the springs 34 which operate to raise the spacing bars 31 are considerably lighter than those employed in the embodiment first described. In fact, the only function performed by the springs 34 in the present case is to raise the spacing bars. The bars are held against downward movement in the present instance by 140 an auxiliary mechanism such as shown in Figures 9 and 10. This mechanism comprises a pair of pivoted stop plates 49 connected by suitable rods 51 to a common actuating lever 52. With the stop plates swung out to the position shown in 145 150

Figure 9 the spacing bars 31 cannot return to their folded positions.

When it is desired to collapse the movable frame in this embodiment the lever 52 is actuated 5 to swing in the stop plates 49, after which the operator swings up the frame 7 and then lowers the same against the bars 31 which causes the latter to fold down and allow the frame 7 to collapse against the base 8.

10 Relating to both embodiments of my invention, it will be noted that the foldable section 3 is being urged outwardly by the action of the spring 17 when the section 3 is in the retracted position. It will also be noted that in this position the bed 15 springs in the frames 7 and 4 are in close proximity. When a person is resting on the folded bed the upper spring is pressed into contact with the lower spring. This locks the two sections of the bed together, and the lower section will not 20 extend itself, even though the release button 21 be accidentally pressed.

I claim:

1. A bed comprising a fixed frame, a frame 25 movable from a retracted position under the fixed frame to a position extended therefrom, a pair of crossed and pivoted equalizing arms connecting said frames for guiding the movable frame in its extending and retracting movements, a supporting leg for the arms adjacent the inter- 30 section thereof, and a coil spring encircling the leg and having arms engaging said equalizing arms for urging the movable frame toward its extended position.

2. A foldable bed section comprising a base, a 35 frame, means pivotally and slidably connecting the frame to the base, said means mounting the frame for pivotal movement about a horizontal axis and adapting the frame for slidable move-

ment from a collapsed position on the base to an elevated position above the base, spacing means mounted on the base and movable to a raised position under the frame for holding the same in the elevated position, and means for moving the spacing means to said position upon upward swinging of the frame.

3. A foldable bed section comprising a base, a frame overlying the base, a hinge connecting the frame and base and slidably mounted for vertical movement on the latter, and a spacing bar pivotally mounted on the base and engageable under the frame for holding the latter in a horizontal elevated position.

4. A foldable bed section comprising a base, a frame overlying the base, a hinge connecting the frame and base and slidably mounted for vertical movement on the latter, and a spring pressed spacing bar pivotally mounted on the base and engageable under the frame for holding the latter in a horizontal elevated position.

5. A foldable bed section comprising a base, a frame overlying the base, a hinge connecting the frame and base and slidably mounted for vertical movement on the latter, a spacing bar pivotally mounted on the base and engageable under the frame for holding the latter in a horizontal elevated position, and a link connecting said frame and bar.

6. A foldable bed section comprising a base, a frame overlying the base, a hinge connecting the frame and base and slidably mounted on the latter, a spacing bar pivotally mounted on the base and engageable under the frame, and a link pivoted at one end to the frame and slidably pivoted at the other end to said bar.

RALPH B. HOSNER.
